DESIGN FOR A SHOE

John J. Walsh, St. Louis, Mo., assignor to Hamilton, Brown Shoe Co., St. Louis, Mo., a corporation of Missouri

Application October 28, 1936, Serial No. 65,552

Term of patent 3½ years

To all whom it may concern:

Be it known that I, John J. Walsh, a citizen of the United States of America, residing in the city of St. Louis and State of Missouri, have invented a new, original, and ornamental Design for Shoes, of which the following is a specification, reference being had to the accompanying drawing, forming a part thereof.

Fig. 1 is a side perspective view of a shoe, showing my new design.

Fig. 2 is a front perspective view of the shoe.

I claim:

The ornamental design for a shoe, substantially as shown.

JOHN J. WALSH.
